CLAIM

The ornamental design for a tooth whitening device, as shown and described.

DESCRIPTION

FIG. 1 is a front perspective view of a tooth whitening device showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines illustrating portions of the tooth whitening device form no part of the claimed design.

1 Claim, 7 Drawing Sheets
